UNITED STATES PATENT OFFICE.

PATRICK J. O'BRIEN, OF MOBILE, NEWFOUNDLAND.

SASH RAISING AND LOCKING DEVICE.

No. 841,810.

Specification of Letters Patent.

Patented Jan. 22, 1907.

Application filed June 19, 1906. Serial No. 322,412.

To all whom it may concern:

Be it known that I, PATRICK J. O'BRIEN, a subject of the King of Great Britain, and a resident of the city of Mobile, Newfoundland, 5 have invented certain new and useful Improvements in Sash Raising and Locking Devices, of which the following is a specification.

My invention relates to certain new and 10 useful improvements in devices for counter-balancing and raising window-sashes and the like and means for locking the sash in any position desired.

Primarily my invention has for its object 15 to provide a device of this character of a very simple and effective construction which can be easily and cheaply manufactured and which will readily and effectively serve its intended purposes.

20 Generically my invention embodies a slotted plate adapted to be attached to the window-frame and containing lock-receiving apertures suitably spaced apart, a device secured to the window for projecting through the slotted plate, and a spring secured to said window-attached devices and to a member on the window-frame for lifting the window at times.

25 My invention also includes an improved lock for coöperating with the lifting devices for holding the window in its adjusted position and comprises a spring-pawl carried by the window and projecting beyond the side thereof for engaging the lock-apertures of the window-frame plate.

30 With other objects in view than have been heretofore enumerated the invention also comprises certain novel construction, combination, and arrangement of parts, all of 40 which will be first described in detail and then be specifically pointed out in the appended claims, reference being had to the accompanying drawings, in which—

Figure 1 is a perspective view of a window 45 with my device applied, parts of the window-frame being shown in section to more clearly illustrate the invention. Fig. 2 is a vertical section of the window and frame with the windows closed. Fig. 3 is a vertical section 50 on the line 3-3 of Fig. 2. Fig. 4 is a detailed perspective view of the latch member adapted to be secured to the window. Fig. 5 is a detail perspective view of the window-frame plate. Fig. 6 is a detailed perspective view 55 of the spring-engaging devices carried by the

window. Fig. 7 is a detailed cross-section showing the manner in which the spring is secured to the window-frame. Fig. 8 is a side elevation of one of the springs. Fig. 9 is a detailed perspective view of keys for engaging the locking device to release it from its locking position. Fig. 10 is a detail section of a portion of the window and frame, illustrating the manner in which the latch member engages the apertured portion in the 65 window-frame.

Referring now to the accompanying drawings, in which like numerals of reference indicate like parts in all of the figures, 1 designates the window, and 2 the frame, all of 70 which may be of the ordinary construction.

In carrying out my invention I provide a plate 3, which I secure to the window-frame by screws 3^a 3^b at a suitable distance alongside of the frame, and the plate 3 is provided 75 with an elongated slot 3^b, terminating at one end in a right-angled extension 3^c, which runs across the plate. The window-frame is cut out to correspond with the slot 3^b 3^c and is of the usual hollow-box type. 80

Within the frame, on each side of the window, I locate a spring 4, one end 4^a of which is secured to a stud-bolt 5, projecting through the slot 3^b and formed with a plate 5^a, which is adapted to be secured in a suitable countersunk portion 1^a on the side of the window 85 1 by screws 6, as shown, the stud-bolt 5 having a spike portion 5^b to enter the window-sash. The other end 4^b of the lower pair of springs is secured to a similarly-formed stud-bolt 7, secured to the window-frame, as 90 shown.

The plates 3 have suitably-spaced latch-receiving apertures 3^d to coöperate with the latch 8, carried by the window, and the latch 95 8 comprises an edge plate 8^a and a key-plate 8^b, formed together and secured to the window-sash in suitable mortises by screws 9, as shown. The latch 8 also comprises a latch member 10, having a spring-arm 10^a secured to the plate 8^a, as at 10^b, and a latch-head 10^c, which projects through an aperture 8^c in the plate 8^a and is adapted to enter the apertures 3^d of the plate 3, as will be clearly understood 100 by reference to the drawings. The latch member 10 also has a heel portion 10^d, provided with a key-receiving aperture 10^e to receive a stud-key 11, which projects through an elongated slot 8^d in the key or guard plate 8^b and by means of which the latch can be 110

withdrawn from the apertures 3^d to permit the springs 4 to aid in raising the window, as will be presently more fully explained.

By providing the slot 3^c, when the windows 5 are closed and the beading 2^a removed from the window-frame the windows 1 can be swung out of the frame when it is desired to remove the windows.

In practice I provide a plate 3 at each side 10 of the lower and upper window-sashes and two springs 4 likewise located for each window, one on each side thereof, and the plates and springs are so arranged as to afford an easy operation of opening the windows.

15 By reference to Fig. 2 of the drawings it will be seen the springs for the upper window 4 are normally compressed when the window is closed, while those for the lower window are normally expanded when the 20 lower window is closed, and the latch devices 8 serve to hold the window in its adjusted position against the tension of the springs 4.

It should be understood that the window-frame is provided with suitable grooves to 25 receive the springs 4.

It will be also noticed that by providing the latch with the spring portion 10^a after the latch has been released from the apertures 3^d by releasing the operator's pressure 30 on the latch the same will be forced against the plate 3 and serve as a friction-retarding means to prevent the springs 4 releasing the windows too rapidly.

Instead of using the springs 4 as a raising 35 means entirely when the latch members are released I may make the tension of the springs 4 only slightly more than counter-balance the weight of the window-sash, and thus aid the manual operation of opening the 40 windows.

The slotted blades 3 serve a twofold function: First, they protect the woodwork of the window-frame and guide the pins 5 and keep them from marring or chipping the 45 grooved portion of the window-frame casing, and, secondly, they serve, in conjunction with the latch, to hold the window in position against the tension of the springs.

From the foregoing description, taken in 50 connection with the accompanying drawings, it is thought the complete construction, operation, and many advantages of my invention will be readily understood by those skilled in the art to which the invention appertains, 55 and I desire to say that many slight changes in the detailed construction, combination, and arrangement of parts may be made without departing from the spirit of the invention or the scope of the appended claims.

60 6c What I claim is—

1. The combination with a window-frame and windows therein, said window-frame having a box portion, of plates having 65 grooves secured to the window-frame, tension-springs held within the window-frame

and secured at one end to the window-frame, stud-bolts carried by the window and projecting through said plate-grooves and secured to the other end of the springs, and means carried by the window and co-operating with said plate for locking the window in various positions substantially as shown and described. 70

2. The combination with a window-frame and windows therein, said window-frame 75 having a box portion, of plates having grooves secured to the window-frame, tension-springs held within the window-frame and secured at one end to the window-frame, stud-bolts carried by the window and projecting through said plate-grooves and secured to the other end of the springs, and means carried by the window and co-operating with said plate for locking the window in various positions, said last-named means 80 comprising a latch member carried by the window, said plates having latch-receiving apertures for co-operating with the latch member, substantially as shown and described. 85

3. The combination with a window-frame, of windows held therein, spring devices within the window-frame and secured at one end to the frame, slotted plates secured to the window-frame, stud-bolts carried by the window and projecting through said slotted plates and into the window-frame and connected with said springs, said plates having 90 latch-receiving apertures, and latch devices carried by the window for engaging said latch, 95 apertures of the plates, substantially as shown and described. 100

4. The combination with a window-frame, and windows mounted therein, of a plate secured to the window-frame, said plate having 105 an elongated aperture and a transverse aperture merging therewith and latch-engaging apertures, a stud-bolt secured to the window and projecting through said slotted plate, a coil-spring within the window-frame and secured at one end of said bolt, a second stud-bolt secured to the window-frame and to the other end of said spring, a latch member carried by the window and comprising a face-plate and a key guard-plate secured to the 110 window-sash, a latch-bolt having a spring portion secured to said face-plate and projecting through an aperture therein to engage the latch-apertures of said first-mentioned plate, said latch-bolt having an apertured head, an operating-key adapted to be inserted into said apertured head through said elongated aperture of said key guard-plate to release said latch from said first-mentioned plate-latch aperture, substantially 115 as shown and described. 120
